UNITED STATES PATENT OFFICE.

EDWARD POOLE, OF PHILADELPHIA, PENNSYLVANIA, ASSIGNOR TO JOHN BROMLEY & SONS.

DESIGN FOR A TABLE-COVER.

UNITED STATES PATENT OFFICE.

DESIGN FOR A TABLE-COVER.

SPECIFICATION forming part of Design No. 21,328, dated February 2, 1892.

Application filed August 31, 1891. Serial No. 404,351. Term of patent 3½ years.

To all whom it may concern:

Be it known that I, EDWARD POOLE, a subject of the Queen of Great Britain, residing at Philadelphia, Pennsylvania, have invented or produced a certain new and original Design for a Table-Cover, of which the following is a full, clear, and exact description, reference being had to the accompanying drawing, forming a part of this specification.

10 My invention relates to the surface ornamentation of a table-cover; and it consists of the design therefor as shown in the accompanying photographic illustration, in which the leading features are the double border A,

15 which does not include the fringe on the edge, surrounding an open-field center, the latter inclosing a center-piece B.

I claim as my invention—

1. The design for a table-cover, substantially as shown and set forth. 20
2. The design for the border A of a table-cover, substantially as shown and set forth.
3. The design for the center-piece B, substantially as shown and set forth.

In testimony whereof I have hereunto affixed my signature this 13th day of July, A. D. 1891.

EDWARD POOLE.
